UNITED STATES PATENT OFFICE.

OVERTON WINSTON, OF MINNEAPOLIS, MINNESOTA.

HEADLIGHT.

1,250,745.

Specification of Letters Patent. Patented Dec. 18, 1917.

Application filed April 3, 1916. Serial No. 88,496.

To all whom it may concern:

Be it known that I, OVERTON WINSTON, a citizen of the United States, residing at Minneapolis, in the county of Hennepin and 5 State of Minnesota, have invented certain new and useful Improvements in Headlights; and I do hereby declare the following to be a full, clear, and exact description of the invention, such as will enable others 10 skilled in the art to which it appertains to make and use the same.

My present invention relates to headlights for automobiles and other vehicles and is in the nature of an improvement on and modification of the construction disclosed and 15 claimed in my co-pending application S. N. 86,851 filed of date March 27, 1916, and entitled "Headlights".

In the said prior application, an oscillating lamp supporting socket is mounted on the pivot that is located above the axis of the reflector, but in the present application, the said socket is mounted on the pivot that 20 is located below the axis of the reflector. 25 Whether the best results can be obtained by placing the pivot above or below the axis of the reflector, depends somewhat on the nature of the lamp and on the form of the reflector. With the pivot below the axis of the 30 reflector, when the lamp is moved upward by oscillatory movement of the socket, it will be given an accelerated rearward movement, and when such arrangement is used in connection with a parabolic reflector, it is a 35 fact that the light beams, at a predetermined point in front of the headlight will be widened when the lamp is moved above the axis of the reflector and at the same time, is given a rearward or receding movement toward 40 the back of the reflector.

The invention is illustrated in the single view which is a vertical section taken centrally through the headlight, some parts being shown in full.

45 Referring to the drawing:

The numeral 1 indicates the casing of an ordinary headlight, such as used on automobiles, and the numerals 2 and 3, indicate, respectively, the reflector and a glass plate 50 or lens of the head light.

The electric light bulb 4 is detachably mounted in a lamp supporting socket 5 which, so far as this present invention is concerned, may take various forms, but may 55 be assumed to be of the type disclosed in my co-pending application above identified.

The axis of the reflector is indicated at y. The lamp socket 5 is connected by pivots 16 to a hollow supporting head 17 that has a threaded shank screwed into the hub of an 60 annular anchoring plate 18 rigidly secured on the back of the reflector 2 and surrounds an axial passage 2^a thereof. The front end of the socket 5 projects through the passage 2^a and works with freedom for vertical movements therein.

For oscillating the lamp socket vertically, I provide upper and lower electro-magnets 19, both of which are rigidly secured to and carried by horizontally projecting upper 70 and lower plates 20 of the hollow bearing head 17.

At their inner extremities, the electro-magnets are provided with pole pieces 19^a and at their outer extremities with pole pieces 19^b. 75 The pole pieces 19^a act upon and limit the oscillatory movements of the rear end of the lamp socket 5, which latter is of iron or steel and serves as an armature.

Small upper and lower lock levers 22 are 80 intermediately pivoted to the upper and lower plates 20 and provided at their inner end with lock heads 23, the outer ends of the levers 22 are yieldingly pressed by a light coiled spring 24 shown as anchored to the 85 plates 20. The outer ends of said levers 22 serve as armatures that are adapted to be retracted by the outer pole pieces 19^b of the respective electro-magnets. The circuit connections for the electro-magnets are not 90 shown, but they are preferably independent of the lamp circuit and so arranged that either electro-magnet may be energized, at will. The manner in which the electro-magnet and lock levers control and lock the 95 movements of the socket is fully disclosed in my said prior application, and since they constitute, *per se*, no feature of the present invention, need not be here further considered. It is sufficient to state that when the

socket is in its horizontal position, as indicated by dotted lines in the drawing, the hot spot of the bulb filament will be at, or approximately at the axis of the reflector and at the focal center thereof, and that when the lamp socket is in the tilted position indicated by full lines in the drawing, the lamp bulb will be raised and retracted so that its filament will then be not only above the axis of the reflector but at a point considerably rearward of a vertical line drawn through the focal center at the reflector. 110

This accelerated rearward movement of the lamp is, of course, due to the location of the pivotal support of the socket below the axis of the reflector, and the movement of the lamp above the axis of the reflector. Otherwise and more broadly stated, the bulb movement is on one side of the axis of the reflector and the pivotal support of the socket is on the other side of the said axis.

10 What I claim is:

In a headlight, the combination with a reflector, of a lamp support and an electric light bulb held thereby within said reflector, said lamp support being mounted to freely

swing in a vertical plane on a fulcrum located at the rear of said reflector and below the axis thereof, and stops limiting the movement of said support so that said lamp will be carried from a position at the axis to a position above the axis of said reflector, and conversely.

In testimony whereof I affix my signature in presence of two witnesses.

OVERTON WINSTON.
